UNITED STATES PATENT OFFICE.

GEORGE L. KELLEY, OF BUFFALO, NEW YORK.

METAL-ROUTING MACHINE.

1,420,319.

Specification of Letters Patent. Patented June 20, 1922.

Application filed March 12, 1921. Serial No. 451,859.

To all whom it may concern:

Be it known that I, GEORGE L. KELLEY, a citizen of the United States, residing at Buffalo, in the county of Erie and State of New York, have invented a new and useful Improvement in Metal-Routing Machines, of which the following is a specification.

This invention relates to engraving, scrib-
ing or routing machines, and is particularly
10 adapted to metal routing or metal plate en-
graving for the production and reproduction
of a variety of predetermined and known
figures and designs and for the production
and reproduction of an infinite variety of
15 confused and indeterminate lines and fig-
ures such as are used on bank notes or safety
papers of various kinds.

The objects of the invention are to pro-
vide a machine of relatively simple construc-
20 tion and few parts which will effectually and
expeditiously engrave, produce and repro-
duce an infinite variety of designs and geo-
metrical figures of predetermined kind; also
to provide a machine which automatically re-
25 peats and reproduces predetermined designs
in some predetermined staggered or over-
lapping arrangement and relation to pre-
viously produced designs; also to provide a
machine which automatically generates a
30 predetermined and otherwise symmetrical
design having in one or more places a pre-
determined mutilation and which produces
successive replicas of such design having
mutilations in different relative positions;
35 also to provide a machine which may be
readily used either as an automatically-con-
trolled router or engraver or as a free or
hand-controlled machine; and also to im-
prove the construction of machines of this
40 character so as to render the working parts
easy of access, replacement and repair. Fur-
ther objects are to improve the construction
of machines of this character in the other
respects hereinafter set forth and claimed.

45 In the accompanying drawings:

Fig. 1 is a sectional elevation of a ma-
chine embodying the invention.

Fig. 2 is a front elevation thereof.

50 Fig. 3 is a fragmentary side elevation
thereof.

Fig. 4 is a fragmentary plan view thereof.

Fig. 5 is a horizontal section thereof on
line 5—5 Fig. 1.

55 Fig. 6 is a top plan view of the major
wheel or supporting member.

Fig. 7 is a vertical section on line 7—7,
Fig. 6.

Figs. 8 and 9 are fragmentary side eleva-
tions of a modified form of the driving con-
nections for effecting automatic movement 60
of the work-supporting table.

Fig. 10 is a sectional elevation of a ma-
chine having a modified form of base and
work-supporting table.

Fig. 11 is a horizontal section on line 65
11—11, Fig. 10.

The present invention, generally stated,
consists in the provision of a rotatable table
or support for the work, which may be ro-
tated either clockwise or counterclockwise, 70
maintained in a stationary position, oscil-
lated, rotated in a step by step movement or
with a combination of rotatable and oscilla-
tory movements, and the provision of a re-
volving support for suitable cutting tools or 75
scribers, which support comprises a major
or sun axis and one or more planetary mem-
bers rotatably mounted on axes removed
from the main axis of the machine, and means
for causing rotation of these members on their 80
planetary axes either clockwise or counter-
clockwise while they are revolving about said
major axis, together with means for automatic-
ally or manually shifting or moving the axes
of the several planetary members to different 85
positions, means for supporting one or more
cutting tools or scribes on one of the plan-
etary members and means for either automatic-
ally during the operation of the machine, or
manually when desired, changing the posi- 90
tion of the cutting tool or tools with refer-
ence to the axis of the machine. The tool is
guided through the desired movements and
gyrations which are determined by the
length of the radius of revolution, the dis- 95
tances between the several axes of the parts,
the relative speeds of revolution and rotation
or counter rotation. The machine further
includes means for placing the cutting tool
into operative position relative to the work 100
and removing the same therefrom, and means
for regulating the depth of the cuts to be
made by the tool.

In the preferred embodiment illustrated,
10 designates a suitable base and 11 a stand-
ard or supporting arm rigidly mounted on
the base. Any suitable form of base and
standard or supporting arm may be pro-
vided. 12 designates the rotatable work-sup-
porting table which may be mounted by any 110

suitable means upon a horizontal portion of the standard. In the machine illustrated, the table is provided on its under side with a substantially annular shoulder 13 which 5 bears upon a horizontal portion 14 of the standard 11. 15 designates a stub shaft which is keyed to the table 12 as at 16, the lower end of the shaft extending through a vertical opening provided at 17 in the standard. The lower end of the shaft 15 is threaded and provided with a suitable washer 18 and nut 19 which maintain the shaft in the standard. 20 designates a friction block and 21 a set screw which is threaded into the 15 standard and bears against the friction block, whereby the table may be secured against rotation on the standard, if desired. The table may be provided with any suitable work-holding or retaining means, slots 22 20 being shown in the embodiment illustrated for the purpose of receiving the usual work-holding dogs or chucks (not illustrated). 23 designates a handle fixed to the table whereby the table may be manually turned. 25 The standard 11 supports the rotatable and gyratory members and cutting tools or scribes of the apparatus and is provided with means for holding the major axial shaft of the cutter regulating and adjusting 30 system. In the preferred form illustrated, the standard 11 terminates in a yoke or neck 24 which is provided with a pair of substantially vertical V-shaped slots or key-ways 25. 26 designates a movable spindle 35 head which is preferably provided with projecting, vertical fins or guides which are adapted to enter the slots or key-ways 25 in the yoke to maintain the spindle head in position while permitting vertical movement of the spindle head within the yoke. 40 As best illustrated in Figs. 1 and 2 of the drawings, it is considered preferable to construct this spindle head in two duplicate parts, each part bearing one of the fins or 45 guides referred to above. These parts also bear lugs or ears 27 which are threaded to receive a screw 28 for securing the parts together. The screw 28 may be provided with a suitable handle 29. 30 designates a sleeve 50 which is keyed as at 32 to the interior of the spindle head 26, and, as illustrated, this sleeve is bored to receive the major spindle 31. By reason of the key and key-way connection between the sleeve and spindle head, 55 the sleeve is free to move vertically in the head but is held from turning therein. The sleeve 30 preferably projects above and below the spindle head and is externally threaded at its upper end as at 34 to receive 60 the regulating nut or wheel 35 by means of which the spindle head and the rotary and gyratory tool supports may be raised or lowered, and the upper end of the bore of the sleeve is preferably enlarged as at 36 to provide a seat for the collar or enlarged por- 65 tion 37 of the spindle. The upper end of the spindle extends through a bearing or boss 38 and carries a pinion 39 in mesh with a pinion 40 which drives a shaft 41. The pinion 39 is slidably mounted on the upper 70 end of spindle 31 with a slot and key connection as indicated at K so that the pinion will turn with the spindle but the spindle may be moved lengthwise through the pinion. The bearing boss 38 for the spindle 75 and the bosses for shaft 41 may be supported in any suitable manner. In the embodiment illustrated, the bearing 38 is formed on a bracket 42 mounted on the standard 11 and this bracket also supports bosses 43 and 44 in 80 which shaft 41 is journaled. 45 designates a gear which is keyed to the shaft 41. 46 designates a shaft carrying a driving pinion 47 and preferably journaled in a boss 48 formed in a portion of the bracket 42 and a 85 second boss or bearing member 49 preferably supported in a bracket 50 secured to the standard 11. 51 designates an arcuate slotted arm in which a pinion 52 is journaled. The slotted arm 51 is adjustably 90 secured to the bracket by means of a set-screw or stud 53. As shown in the drawings, it is considered preferable that the pinion 52 be mounted on the slotted arm 51 by detachable means such as the bolt and nut 95 51 shown, so that if it is desired to change the gear ratio at this point, the pinion 52 may be replaced by a pinion or gear of different diameter, proper adjustment being made of the slotted arm 51 through means 100 of the set-screw 53 to compensate for the difference in gear diameter. By these means, suitable change may be made in the relative rate of speed at which the pinion 47 is driven. In the embodiment illustrated, 105 the shaft 46 is provided with a pinion 54 which is in mesh with pinion 55 secured to the shaft 56, whereby rotation of the spindle 31 is transmitted to the shaft 56. The shaft 56 is journaled at one end in a part of 110 the bracket 50, the other end of the shaft being journaled in a bracket 57 adjacent the table. A pinion 58 is secured to the lower end of shaft 56, which pinion meshes with a pinion 59 rotatably mounted on a 115 swinging plate 60. The plate 60 is preferably mounted to swing about the lower end of the shaft 56 as an axis and carries a second pinion or gear 61 which is in mesh with pinion 59 but is not in direct engagement 120 with the pinion 58. 62 designates a gear mounted on the bracket 57, this gear 62 being in mesh with a driving gear or wheel 63 rigidly secured to or mounted on the rotatable work-supporting table. The swinging 125 plate 60 acts, when swung in one direction, to position the gear 59 as a driving connection between pinion 58 and gear 62, and when swung in the other direction operates to engage pinion 61 with gear 62, whereby 130

- the drive will be from pinion 58 to pinion 59, thence through pinion 61 to gear 62, the result being a reversal of the drive relatively to the driving connection effected by 5 swinging movement in the first named direction. The swinging plate 60 is provided with a handle 64 and is also provided with means for releasably holding said plate with its gearing in the desired driving position.
- 10 In the form illustrated, these means comprise a pin or lug 65 mounted on the swinging arm, and a plurality of recesses 66 in the bracket 57, into any one of which recesses the pin or lug is adapted to engage. By a 15 suitable selection and change of the pinions which take the drive from shaft 41, any desired relative speeds or rate of rotation of the shaft 56 may be obtained when the spindle is turned, and by suitable adjustment of 20 the swinging pinion-supporting plate at the lower end of shaft 56, an adjustment may be secured whereby the table remains stationary or is rotated clockwise or counterclockwise at the option of the operator.
- 25 The invention also includes means which are readily accessible to the operator for raising and lowering the spindle head, spindle and associated parts. In the apparatus illustrated, these means comprise a rack bar 30 67 which is secured to the spindle head 26. Cooperating with this rack bar is a bell crank lever 68, pivoted on a suitable pin 69 and operated through means of a chain 70 which is connected at one end to the bell 35 crank lever and extends over guide pulleys 71 journaled in the hollow standard of the machine. The bell crank lever 68 has suitable teeth engaging the teeth of rack bar 67. The chain 70 is connected at its other end to 40 a suitable counterweight 72 and is actuated from a treadle or foot pedal 73 connected to a lever 74 which is pivoted to the base of the machine. The lever 74 is connected to the counterweight 72 by means of a link 75, whereby when the treadle or pedal is depressed, the bell crank lever raises the rack bar and spindle head. The spindle head and supporting members and the like are of sufficient weight to overcome the counterweight 45 50 to move to and remain in work-engaging position. Thus, when the tool has been set to work to a desired depth, by adjustment of wheel 35, it may be permitted to be engaged with and disengaged from the work by 55 manipulation of treadle 73. While the spindle-head raising and lowering mechanism illustrated is preferred at this time, it is obvious that other mechanism may be utilized for the same purpose and the invention is in 60 no wise to be considered restricted to the particular form shown.
- The mechanism for automatically regulating the movements of the cutters or tools consists of a plurality of supporting members or wheels arranged to revolve about the 65 axis of the spindle head. In defining or explaining the movements of the parts, the axis of the spindle head may be considered as the major or sun axis and the supporting members include one or more gyroscopic or 70 planetary members which are rotatable upon their own axes and revolve about the major axis of the machine. The several supporting members have suitable driving connections so that upon movement being imparted to 75 one of the supporting members, movement may be transmitted to the other supporting members. Thus, when the major supporting member or wheel is turned about the major axis, the gyroscopic members will be revolved 80 about that major axis and at the same time may be held stationary on their axes or rotated either clockwise or counterclockwise, as the mechanism may be adjusted, to inscribe the desired figure or design. Suitable 85 means are provided for connecting these supporting members or wheels to the spindle of the machine.
- In the preferred embodiment illustrated, 90 76 designates a spider which is splined to the lower end of spindle 31 and which is connected to and holds the major support or wheel 77. The support or wheel 77 is provided with a radial slot 78 adapted to receive a sliding block 79 which is bored and threaded as at 80 to receive a worm rod 81 journaled in a boss 82 on wheel 77, to move lengthwise of the worm rod by reason of the engagement of the threaded portion 80 with the threads of the worm rod. 83 designates 95 a handle by means of which rod 81 may be turned, and 84 designates a collar fixed to the worm rod at the inner side of the boss 82 which retains the rod in position in the wheel and prevents it from being withdrawn 100 from the boss 82. Block 79 is slotted or recessed at one side as at 85, and 86 designates a worm wheel journaled in the major wheel or support 77, this worm wheel preferably carrying an indicator 86^a and engaging with 105 the worm rod 81. The slot 85 permits of the sliding block 79 passing the worm wheel and indicating device without interference when the block is moved.
- Means are provided for connecting the 110 spindle or major axis of the machine and the supporting members or wheels so that when the major wheel or support is revolved, the gyroscopic members will be rotated about their respective axes and their axes shifted either 115 towards or from the major axis of revolution, as desired. In the preferred means illustrated, 87 designates a gear fixed to the spindle sleeve 30 adjacent its lower end and 88 designates a bracket secured to the lower 120 end of the sleeve 30. Bracket 88 is provided with a slotted portion 89, the slot in which follows the contour of the gear 87. 90 designates an idler gear mounted on the slotted portion 89 of the bracket and adapted to 125 130

mesh with a gear 91 keyed to a shaft 92 which is journalled in a boss 93 on the major wheel 77. Shaft 92 carries a pinion 94 which is in mesh with and drives a pinion 95 fixed on a substantially horizontal shaft 96 journalled in suitable bearings in the lower part of major wheel 77. The idler gear 90 may be removed from the slotted portion 89 of its supporting arm if desired, 10 and replaced by a gear of different diameter, for the purpose of changing the rate of movement of the shaft 96 relatively to the rate of movement of the spindle 31, it being apparent that when the major wheel 77 is 15 turned about its axis the spindle 31 will be turned and the gear 87, being stationarily held on the spindle sleeve, will rotate gear 90 as that gear revolves about the periphery of gear 87, resulting in rotation of the shaft 20 96 through the medium of gears 91, shaft 92 and the bevel gears 94 and 95. 97 designates a pinion slidably mounted on the outer end of shaft 96 and adapted to be turned thereby. In order to permit this sliding mounting, as illustrated, the shaft may be fluted 25 and the pinion provided with suitable recesses, whereby lengthwise movement of the pinion on the shaft is permitted, but the pinion will rotate or be turned with the 30 shaft. Pinion 97 is adapted to mesh with a gear 98 keyed to worm rod 81, whereby when the major wheel is turned about its axis, movement may be transmitted to shaft 96 and through shaft 96 by means of pinion 97 35 and gear 98 to the worm rod 81 to move slide block 79 toward or from the axis of the spindle head of the machine.

Sliding block 79 is adapted to support the next lower planetary wheel or supporting member 98^a and for this purpose is provided with a depending stem 99. 100 designates a spider having a collar portion 101 which is rotatably mounted on the lower end of stem 99. Spider 100 is held in place on stem 45 99 by means of a washer and nut 102. 103 designates a bevel pinion rigidly mounted on the upper part of collar portion 101 and 104 designates a planetary wheel or supporting member connected to spider 100. 50 105 designates a pair of supporting arms which depend from the lower part of the block 79 and are rigid therewith, and 106 designates a gear rigidly connected to these supporting arms. 107 designates a slotted 55 arm having a hub portion 107^a fixed to collar portion 101 of spider 100 and rotatable with that collar portion within and relatively to gear 106. 108 and 109 designate a pair of bevel pinions mounted on shaft 96 60 of the major supporting wheel. As in the case with the pinion 97, these bevel pinions are so keyed to the shaft that they may be moved lengthwise without interfering with their driving connection with the shaft. 65 Pinions 108 and 109 are provided with set-

screws 108^a and 109^a or similar fastening devices whereby they may be secured at any desired place on the shaft and are adapted to be selectively engaged with bevel pinion 103, whereby rotation of the shaft 96 will 70 drive pinion 103 in a clockwise or counter-clockwise direction as may be desired. 110 designates an idler gear mounted on the slotted portion of arm 105. As in the case of gear 90 of the major wheel, gear 110 may 75 be replaced by a gear of different diameter so as to change the ratio of the drive. 111 designates a gear fixed to a stub shaft 112 journalled in planetary wheel 98^a and meshing with idler gear 110. Stub shaft 112 carries a bevel pinion 113 meshing with a bevel pinion 114 on a lower horizontal shaft 115.

The planetary wheel or supporting member 98^a is provided with a radial slot 116 which is similar to the slot 78 of the major 85 wheel or supporting member. 117 designates a sliding block which is preferably of the same form as the sliding block 79 of the major wheel, which block is movable in the slotted portion 116 of the wheel and is propelled by a worm rod 118 provided with a handle 119. 120 designates the indicating device for the planetary wheel, which device is of similar form and operatively connected to the worm rod 118 in the manner described 90 for corresponding parts in the major wheel. 121, 122 and 123 designate pinions slidably mounted on shaft 115, these pinions being similar in form to and functioning like pinions 108, 109 and 97 of the major wheel, and 100 124 designates a gear fixed to worm rod 118 for transmitting motion from pinion 123 to the worm rod.

According to the invention, the machine is provided with one or more planetary wheels 105 or supporting members. In the embodiment illustrated there are shown two planetary wheels, in which case the sliding block 117 supports and provides an axis for the second planetary wheel 125 in the same manner in which the block 79 of the major wheel provides an axis for the first planetary wheel or support. The planetary wheel or support 125 is of like construction to the first planetary wheel or support described, and 110 carries a sliding block 126 which is adapted to be moved radially of the wheel in a slot 127 upon movement of a worm rod 128 provided with a handle 129. 130 designates a pinion keyed to the collar of a spider 131 120 which surrounds the depending portion of block 117 and 132 designates a slotted arm mounted on the collar of the spider 131, 133 the relatively fixed gear depending from sliding block 117, 134 a pinion journalled in 125 arm 132, 135 and 136 a gear and connected shaft to take the drive from pinion 134, 137 a lower horizontal shaft, 138 a pinion on shaft 136 which meshes with a pinion 139 fixed to shaft 137, and 140 and 141 engage- 130

able pinions on shaft 137 and worm rod 128, respectively, all of these parts being like corresponding parts in the other supporting wheels described. The sliding block 126 is 5 adapted to support a suitable tool holder. In the embodiment illustrated, 142 designates an electric motor connected to the sliding block 126, which motor is adapted to drive the chuck 143 which carries a tool 144. 10 It is obvious that the motor may be dispensed with if desired, or that other well known forms of tool chucks or holders may be connected to the sliding block if desired.

The supporting members or wheels are 15 preferably provided with a plurality of radially arranged worm rods for the purpose of permitting the suspension or supporting of several gyratory wheels from the major wheel or from another gyratory wheel, if 20 desired. This construction also permits of the use of several tool holders and tools with any one of the gyratory wheels or the major wheel or permits the attachment, on any one or all of the supporting wheels, of traveling 25 counterweights, as W for automatically balancing the wheels. The arrangement and construction of these additional worm rods on the different wheels may be similar, so in these respects the construction of one wheel 30 only need be described in detail. In the embodiment best illustrated in Figs. 5 and 6, worm rod 81 of the major wheel carries at its inner end a bevel pinion 145 which meshes with and drives pinions 146 and 147 fixed respectively to radially arranged worm rods 35 148 and 149. As heretofore stated, these worm rods 148 and 149 may carry sliding blocks similar to block 79 of the major wheel, each of which blocks may serve as an axis 40 for a gyratory wheel or for a tool holder, or may carry suitable weights to automatically balance the wheel when the block 79 is moved towards or from the pivotal axis of the wheel. Any suitable number of these 45 worm rods may be provided.

Figs. 8 and 9 illustrate a modified form of driving connection between shafts 41 and 46 in which embodiment shaft 41 carries a gear wheel 45^a which drives a pinion 52^a mounted 50 on an arcuate slotted arm 51^a, these parts being like the corresponding parts illustrated in Figs. 2 and 3. 47^a designates a gear fixed to a stub shaft 48^a journaled on an arm 49^a of bracket 42^a and 50^a designates a lever 55 or crank arm rigidly connected to shaft 48^a. 51^b designates a link which connects crank arm 50^a to a crank arm 52^b which rocks a shaft 53^a which is suitably journaled in brackets 42^a and 54^a. A sector gear 55^a is 60 fixed on shaft 53^a adjacent the bracket 54^a.

The sector gear 55^a secured on the opposite end of shaft 53^a, engages a gear 56^a which turns shaft 46 mounted in an arm of bracket 54^a. Shaft 46 has fixed on its outer end a 65 pinion 58^a which meshes with and drives a

pinion 59^a fixed to an end of vertical shaft 56^b. The selective connections between the lower end of shaft 56^b and pinion 62 which drives the rotatable table are similar to the corresponding parts shown in Fig. 1 between 70 shaft 56 and pinion 62. As illustrated, crank arms 50^a and 52^b are of different lengths and the extent of the rocking or turning movement of shaft 53^a is determined by the difference between the lengths of the crank 75 arms. Different movements of rock shaft 53^a may be effected by the different adjustments of the ends of the link 51^b in the slots of the crank arms, so as vary the extent to which shaft 53^a is turned. The movement of 80 shaft 53^a is communicated to shaft 56^b through sector gear 55^a, gear 56^a, shaft 46 and pinions 58^a and 59^a and results in the transmission of oscillatory movement to the work-supporting table. 85

Figs. 10 and 11 show the invention as applied to a machine having a cylindrical work-supporting table. In this modified form, the tool or cutter-controlling mechanism and the driving connections for shaft 90 56 or 56^b are of the type illustrated in Figs. 1 to 9 inclusive. Referring to Fig. 10, 12^c designates a cylindrical table or work support mounted to turn in brackets 13^c on the horizontal table 14^c. 15^c designates a hollow 95 spindle which is fixed to table 14^c by a pin 16^c. Spindle 15^c is externally threaded so as to engage the internally threaded portion of an adjusting collar 17^c which has its periphery formed as a worm wheel at 18^c. 100 19^c designates a worm carried by a shaft 20^c provided with a handle 21^c. The underside of adjusting collar 17^c bears upon an edge of an externally threaded sleeve 22^c in which the hollow spindle 15^c is movable. 105 The sleeve 22^c is provided with a shoulder 23^c which acts as a stop to engage a worm collar 24^c which surrounds and is in threaded engagement with sleeve 22^c and which rests upon a bearing shoulder 25^c provided in 110 the base of the machine. 26^c designates a worm shaft having a handle 27^c and journaled in a bearing 28^c. As the adjusting collar 24^c supports the sleeve, hollow spindle and table upon the shoulder 25^c of the 115 machine, actuation of worm shaft 26^c in one direction will raise the horizontal and cylindrical tables and then actuation of worm shaft 20^c will further raise the tables by moving the hollow spindle 15^c upwardly 120 in its sleeve 22^c. 62^c designates a pinion corresponding to pinion 62 shown in Fig. 1 and 63^c a gear through means of which the table 12^c is turned.

Fig. 10 illustrates a modified form of 125 standard and counterweight, in this form the standard 29^c having a side vertical portion 30^c of greater length than the corresponding part shown in Fig. 1, the counterweight 31^c shown in this embodiment be- 130

ing substantially cylindrical in form and suspended in the side vertical portion 30° of the standard 29°.

The operation of the machine is as follows:

The work or material to be routed or engraved is held on the rotatable table by means of suitable chucks or dogs engaging the slots 22 of the table. By actuation of the handles 83, 119 or 129, the tool 144 may be moved towards or from the axis of the machine. The pinion 108 or the pinion 109 may be set to engage the pinion 103 which rotates the first planetary member. If with these gears set in the manner indicated, the major wheel or supporting member 77 is turned by hand, the result will be that the cutting tool is revolved about the axis of the spindle 31 and at the same time is rotated either clockwise or counterclockwise, depending upon which of the pinions 108 and 109 is in mesh with the gear 103. This action may be modified, if desired, by engaging the pinion 97 with the gear 98, in which case in addition to the major revolution and the clockwise or counterclockwise rotation, the sliding block 79 will, as the revolution progresses, be moved toward the axis of revolution, resulting in a modification of the design. One of the movable pinions on the shaft 115 of the first planetary member may be engaged with the axial pinion of the second planetary member so as to result in rotation of the second planetary member about the axis of the sliding block 117; likewise the sliding pinion on the end of the shaft 115 may be engaged with the worm rod driving pinion of the first planetary member resulting in a shifting of the axis of rotation of the second planetary member in the manner described above. In addition to these movements of the cutting tool or scribe, which may be regulated and adjusted to result in the production of an infinite number of designs, in straight lines, in angles, squares, polygons, tangents, circles and their many distortions or parts such as chords, arcs, involutes, spirals and ellipses; by suitable combinations of revolution and rotation, modified in some instances during the revolutions by actuation of the worm rods, tangential arcs, abscissas, parabolas, hyperbolas, ovals, cycloids, epicycloids, hypercycloids, interior epicycloids, scrolls, helicals, ionic volutes, etc. may be generated. In addition to the generation of the above figures and problems, the designs or figures may be modified by suitable movement of the work-supporting table which may be rotated when the supporting wheels are revolved and the spindle 31 is turned. This turning movement of the spindle is transmitted to the shaft 56, from which shaft it is transmitted to rotate, either in a clockwise or counterclock-

wise direction, the table 12, through the medium of pinions and gears 59, 60, 61 and 62. It is thus possible to set the parts of the machine for a desired revolution and co- or counter-rotation of the cutting tools or scribes, to modify these movements by manual operation of the several worm rods in the supporting members, to shift the axes of the supporting members or of the tools, and in addition thereto, to rotate the work-supporting table either clockwise or counterclockwise or to advance the supporting table with an intermittent rotary movement or to set up any modified movement of the table desired. The result may be, if desired, a cutting or engraving of the highly confused and intricate figures and lines used on bank notes or safety paper.

I claim as my invention:

1. In a machine of the character described, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, and selective means connecting said rotatable device and said gyratory device and actuated by movement of said rotatable device about its axis for rotating said gyratory device in or counter to the direction of revolution of said rotatable device.

2. In a machine of the character described, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, and means connecting said devices and actuated by movement of said rotatable device about its axis for shifting the axis of said gyratory device either towards or from the axis of said rotatable device.

3. In a machine of the character described, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, and releasable means connecting said devices and actuated by movement of said rotatable device about its

axis, for shifting the axis of said gyratory device either towards or from the axis of said rotatable device or for permitting the axis of said gyratory device to remain stationary relatively to the axis of said rotatable device.

4. In a machine of the character described, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, means actuated by movement of said rotatable device about its axis for rotating said gyratory device, and manually operable means for shifting the axis of rotation of said gyratory device towards or from the major axis of revolution of said devices.

5. In a machine of the character described, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, means connecting said devices and actuated by movement of said rotatable device about its axis for shifting the axis of said gyratory device either towards or from the axis of said rotatable device, and manually operable means for shifting the axis of rotation of said gyratory device towards or from the major axis of revolution of said device.

6. In a machine of the character described, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, means connecting said devices and actuated by movement of said rotatable device about its axis for shifting the axis of said gyratory device either towards or from the axis of said rotatable device, and means for automatically indicating the extent of movement of said axis of rotation towards or from the major axis of revolution of said devices.

7. In a machine of the character described, tool-supporting and guiding means comprising in combination, a rotatable device having a major axis of revolution, a gyratory device

supported from said rotatable device and having an independent axis of rotation, whereby said gyratory device is adapted to revolve about said major axis with said rotatable device and to rotate about its independent axis, a tool holder connected to said gyratory device, means actuated by movement of said rotatable device about its axis for rotating said gyratory device, manually operable means for shifting the axis of rotation of said gyratory device towards or from the major axis of revolution of said devices, and means for automatically indicating the extent of movement of said axis of rotation towards and from the major axis of revolution of said devices.

8. In a machine of the character described, the combination of means for supporting work to be operated upon, and tool-supporting and guiding means comprising a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, and means connecting said work-supporting means and said tool-supporting and guiding means for automatically rotating said work-supporting means when said tool-supporting and guiding means are revolved.

9. In a machine of the character described, the combination of means for supporting work to be operated upon, and tool-supporting and guiding means comprising a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, and means connecting said work-supporting means and said tool-supporting and guiding means, said means including selective driving connections whereby said work-supporting means may be rotated in or counter to the direction of revolution of said tool-supporting and guiding means.

10. In a machine of the character described, the combination of a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, and means for raising and lowering said rotatable and said gyratory devices.

11. In a machine of the character de-

scribed, tool-supporting and guiding means comprising in combination, a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, selective means connecting said rotatable device and said gyratory device and actuated by movement of said rotatable device about its axis for rotating said gyratory device in or counter to the direction of revolution of said rotatable device, and means for raising and lowering said tool-supporting and guiding means.

12. In a machine of the character described, the combination of means for supporting work to be operated upon, and tool-supporting and guiding means comprising a rotatable device having a major axis of revolution, a gyratory device supported 20 from said rotatable device and having an independent axis of rotation, whereby said gyratory device is adapted to revolve about said major axis with said rotatable device and to rotate about its independent axis, a 25 tool holder connected to said gyratory device, means connecting said work-supporting means and said tool-supporting and guiding means, said means including selective driving connections whereby said work- 30 supporting means may be rotated in or counter to the direction of revolution of said tool-supporting and guiding means, and means 35 for raising and lowering said tool-supporting and guiding means.

40 13. In a machine of the character described, the combination of means for supporting work to be operated upon, and tool-supporting and guiding means comprising a rotatable device having a major axis of revolution, a gyratory device supported from said rotatable device and having an independent axis of rotation, whereby said gyratory device is adapted to revolve about said major axis with said rotatable device 45 and to rotate about its independent axis, a tool holder connected to said gyratory device, and means connecting said work-supporting means and said tool-supporting and guiding means for automatically rotating said work-supporting means when said tool-supporting and guiding means are revolved, said means including selective driving connections whereby said work-supporting means may remain stationary or be moved 50 either in or counter to the direction of revolution of said tool-supporting and guiding means.

14. In a machine of the character described, the combination of means for supporting work to be operated upon, and tool-

supporting and guiding means comprising a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, means connecting said work-supporting means and said tool-supporting and guiding means for automatically rotating said work-supporting means when said tool-supporting and guiding means are revolved, and means for locking said work-supporting means against rotation. 70 75 80

15. In a machine of the character described, the combination of means for supporting work to be operated upon, and tool-supporting and guiding means comprising a rotatable device having a major axis of revolution, a gyratory device supported from said rotatable device and having an independent axis of rotation, whereby said gyratory device is adapted to revolve about said major axis with said rotatable device and to rotate about its independent axis, a tool holder connected to said gyratory device, means connecting said work-supporting means and said tool-supporting and guiding means for automatically rotating said work-supporting means when said tool-supporting and guiding means are revolved, said means including selective driving connections whereby said work-supporting means may remain stationary or be moved either in or counter to the direction of revolution of said tool-supporting and guiding means, and means for locking said work-supporting means against rotation. 105

16. In a machine of the character described, the combination of means for supporting work to be operated upon, and tool-supporting and guiding means comprising a rotatable device having a major axis of revolution, a gyratory device supported from said rotatable device and having an independent axis of rotation, whereby said gyratory device is adapted to revolve about said major axis, a tool holder connected to said gyratory device, and means connecting said work-supporting means and said tool-supporting and guiding means, said means including connections for oscillating said work-supporting means when said tool-supporting and guiding means are revolved. 110 115 120

17. In a machine of the character described, the combination of means for supporting work to be operated upon, and tool-supporting and guiding means comprising 125 a rotatable device having a major axis of revolution, a gyratory device supported from said rotatable device and having an independent axis of rotation, whereby said gyratory device is adapted to revolve about 130

- said major axis with said rotatable device and to rotate about its independent axis, a tool holder connected to said gyratory device, means connecting said work-supporting 5 means and said tool-supporting and guiding means, said means including connections for oscillating said work-supporting means when said tool-supporting and guiding means are revolved, and means for initiating 10 the oscillations of said work-supporting means in a reverse direction.
18. In a machine of the character described, the combination of a tool holder and supporting and guiding means for said tool holder comprising a rotatable device having a major axis of revolution, a gyratory device supported on a separate axis on said rotatable device, connections between said is connected, a sliding block mounted in said 20 rotatable device, connections between said sliding block and said gyratory device, said block having a part constituting a pivotal axis for said gyratory device, a worm rod in said rotatable device and engaging said 25 sliding block, and selective means connecting said worm rod and said rotatable device for moving said block when said rotatable device is revolved.
19. In a machine of the character described, the combination of a tool holder and supporting and guiding means for said tool holder comprising a rotatable device having a major axis of revolution, a gyratory device supported on a separate axis on said 30 rotatable device and to which said tool holder is connected, a sliding block mounted in said rotatable device, connections between said sliding block and said gyratory device, said block having a part constituting a 35 pivotal axis for said gyratory device, a worm rod in said rotatable device and engaging said sliding block, and releasable driving connections between said worm rod and said rotatable device whereby said worm rod may be driven 40 or permitted to remain stationary while said rotatable device is being revolved, a handle on said worm rod whereby said worm rod may be manually actuated when released from driving connection with said rotatable device, and means for automatically indicating the extent of movement of said block 45 on said worm rod.
20. In a machine of the character described, the combination of a tool holder and supporting and guiding means for said tool holder comprising a rotatable device having a major axis of revolution, a gyratory device supported on a separate axis on said 50 rotatable device and to which said tool holder is connected, a sliding block mounted in said rotatable device, connections between said sliding block and said gyratory device, said block having a part constituting a pivotal axis for said gyratory device, a worm rod in 55 said rotatable device and engaging said sliding block, releasable driving connections between said worm rod and said rotatable device whereby said worm rod may be driven or permitted to remain stationary while said 60 rotatable device is being revolved, and a handle on said worm rod whereby said worm rod may be manually actuated when released from driving connection with said rotatable device, and means for automatically indicating the extent of movement of said block 65 on said worm rod.
21. In a machine of the character described, the combination of a tool holder and supporting and guiding means for said tool holder comprising a rotatable device having a major axis of revolution, a gyratory device supported on a separate axis on said 70 rotatable device and to which said tool holder is connected, a sliding block mounted in said rotatable device, connections between said sliding block and said gyratory device, said block having a part constituting a pivotal axis for said gyratory device, a worm rod in 75 said rotatable device and engaging said sliding block, selective means connecting said worm rod and said rotatable device for moving said block when said rotatable device is 80 revolved, and means for automatically indicating the extent of movement of said block on said worm rod.
22. In a machine of the character described, the combination of a tool holder and supporting and guiding means for said tool holder comprising a rotatable device having a major axis of revolution, a gyratory device supported on a separate axis on said 85 rotatable device and to which said tool holder is connected, a sliding block mounted in said rotatable device, connections between said sliding block and said gyratory device, said block having a part constituting a pivotal axis for said gyratory device, a worm rod in 90 said rotatable device and engaging said sliding block, selective means connecting said worm rod and said rotatable device for moving said block when said rotatable device is 95 revolved, and means for automatically indicating the extent of movement of said block on said worm rod.
23. In a machine of the character described, the combination of means for supporting work to be operated upon, a supporting and guiding device revoluble about a fixed axis and comprising a relatively stationary gear wheel circumscribing said fixed axis, a supporting wheel mounted to revolve about said fixed axis, a pinion mounted on 100 said supporting wheel to mesh with and rotate around the periphery of said stationary gear wheel, a gyratory supporting member pivoted to said supporting wheel, a tool holder mounted on said gyratory supporting member, and connections between said pinion and said gyratory member, whereby said gyratory member is rotated upon revolution of said pinion about said stationary 105 gear wheel.

24. In a machine of the character described, the combination of means for supporting work to be operated upon, a tool-supporting and guiding device having a fixed axis of revolution and comprising a rotatable device arranged to revolve about said fixed axis, a gyratory device pivotally supported from said rotatable device, a second gyratory device pivotally supported from said first named gyratory device, a holder for a tool on said second gyratory device, and driving connections between said gyratory devices and said rotatable device for producing gyrations of said gyratory devices when said rotatable device revolves about its fixed axis.

25. In a machine of the character described, the combination of means for supporting work to be operated upon, a tool-supporting and guiding device having a fixed axis of revolution and comprising a rotatable device arranged to revolve about said fixed axis, a gyratory device pivotally supported from said rotatable device, a second gyratory device pivotally supported from said first named gyratory device, a holder for a tool on said second gyratory device, and selective driving connections between said gyratory devices and said rotatable device for producing gyrations of said gyratory devices when said rotatable device revolves about its fixed axis.

26. In a machine of the character described, the combination of means for supporting the work to be operated upon, a tool-supporting and guiding device having a fixed axis of revolution and comprising a rotatable device arranged to revolve about said fixed axis, a gyratory device pivotally supported from said rotatable device, a second gyratory device pivotally supported from said first named gyratory device, a holder for a tool on said second gyratory device, and selective driving connections between said gyratory devices and said rotatable device for revolving said gyratory devices about said fixed axis and rotating said gyratory devices on their pivots either in or counter to the direction of revolution while they are being revolved.

27. In a machine of the character described, tool-guiding means comprising a rotatable device having a fixed axis of revolution, a gyratory device pivoted to said rotatable device, and connections between said rotatable device and said gyratory device for rotating said gyratory device about its pivot while said rotatable device and said gyratory device revolve about said fixed axis.

28. In a machine of the character described, tool-guiding means comprising a rotatable device having a fixed axis of revolution, a gyratory device pivoted to said rotatable device, and selective driving connec-

tions between said rotatable device and said gyratory device for rotating said gyratory device about its pivot either in or counter to the direction of revolution of said tool-guiding means when said rotatable device and said gyratory device are revolved about said fixed axis.

29. In a machine of the character described, tool-guiding means comprising a rotatable device having a fixed axis of revolution, a gyratory device pivoted to said rotatable device, means for moving the pivotal axis of said gyratory device towards or from said fixed axis, and driving connections between said rotatable device and said gyratory device for rotating said gyratory device about its pivotal axis when said rotatable device and said gyratory device are revolved about said fixed axis.

30. In a machine of the character described, tool-guiding means comprising a rotatable device having a fixed axis of revolution, a gyratory device pivoted to said rotatable device, and driving connections between said rotatable device and said gyratory device for rotating said gyratory device about its pivotal axis and for moving the pivotal axis of said gyratory device towards or from said fixed axis when said rotatable device is revolved about said fixed axis.

31. In a machine of the character described, the combination with a work-supporting table, of tool-guiding means comprising a rotatable device having a fixed axis of revolution, a gyratory device pivoted on a movable axis on said rotatable device, connections between said rotatable device and said gyratory device for rotating said gyratory device about its pivotal axis and shifting said pivotal axis towards or from said fixed axis when said rotatable device is revolved about its fixed axis, and connections between said rotatable device and said work-supporting table for revolving said work supporting table when said tool-guiding means are revolved about said fixed axis.

32. In a machine of the character described, the combination of a rotatable spindle, means for supporting said spindle, a sleeve surrounding said spindle and in which said spindle turns, a device fixed to one end of said spindle to rotate therewith, a gear fixed on an end of said sleeve, a pinion journaled in a part of said rotatable device and meshing with said gear, a gyratory device pivoted on a movable axis on said rotatable device, and driving connections between said pinion and said gyratory device for rotating said gyratory device and shifting the pivotal axis of said gyratory device towards or from the axis of said spindle when said rotatable device is revolved on its spindle.

33. In a machine of the character described, the combination of a rotatable spin-

5 dle, means for supporting said spindle, a sleeve surrounding said spindle and in which said spindle turns, a device fixed to one end of said spindle to rotate therewith, a gear fixed on an end of said sleeve, a pinion journalled in a part of said rotatable device and meshing with said gear, a gyratory device pivoted on a movable axis on said rotatable device, a shaft journalled in said rotatable device, a gear fixed to said shaft and in driving engagement with said pinion, an axial pinion fixed to said gyratory device, and driving connections between said shaft and said axial pinion for rotating said gyratory device when said rotatable device is turned on its spindle.

34. In a machine of the character described, the combination of a rotatable spindle, means for supporting said spindle, a 10 sleeve surrounding said spindle and in which said spindle turns, a device fixed to one end of said spindle to rotate therewith, a gear fixed on an end of said sleeve, a pinion journalled in a part of said rotatable device and meshing with said gear, a gyratory device pivoted on a movable axis on said rotatable device, a shaft journalled in said rotatable device, a gear fixed to said shaft and in driving engagement with said pinion, an axial pinion fixed to said gyratory device, a pinion fixed to said shaft to turn therewith, a horizontal shaft journalled in said rotatable device, a pinion on said horizontal shaft engaging said pinion on said first named shaft, 25 and a pair of pinions slidably mounted on said horizontal shaft to selectively engage said axial pinion on said gyratory device.

35. In a machine of the character described, the combination of a rotatable spindle, means for supporting said spindle, a 40 sleeve surrounding said spindle and in which said spindle turns, a device fixed to one end of said spindle to rotate therewith, a gear fixed on an end of said sleeve, a pinion journalled in a part of said rotatable device and meshing with said gear, a gyratory device pivoted on a movable axis on said rotatable device, a shaft journalled in said rotatable device, a gear fixed to said shaft and in driving engagement with said pinion, an axial pinion fixed to said gyratory device, a pinion fixed to said shaft to turn therewith, a horizontal shaft journalled in said rotatable device, a pinion on said horizontal shaft engaging said pinion on said first named shaft, 45 a pair of pinions slidably mounted on said horizontal shaft to selectively engage said axial pinion on said gyratory device, a worm rod journalled in said rotatable device, a 50 sliding block in said rotatable device mounted to move on said worm rod, a driving gear on said worm rod, and a pinion slidably mounted on said horizontal shaft to selectively engage said worm rod driving gear.

36. In a machine of the character de-

scribed, the combination of tool-guiding means comprising a rotatable device having a major axis of revolution, a support for said rotatable device, a member radially movable on said rotatable device, a gyratory 70 device pivoted to said radially movable member, said radially movable member having a part constituting a separate axis of rotation for said gyratory device, a member radially movable on said gyratory device, a tool 75 holder connected to said last named radially movable member, and connections between said rotatable device and said gyratory device for rotating said gyratory device about its separate axis when said tool-guiding means are revolved about said major axis and for shifting said radially movable members to shift the separate axes of said gyratory device and said tool holder.

37. In a machine of the character described, the combination of tool-guiding means comprising a rotatable device having a major axis of revolution, a support for said rotatable device, a member radially movable on said rotatable device, a gyratory 90 device pivoted to said radially movable member, said radially movable member having a part constituting a separate axis of rotation for said gyratory device, a member radially movable on said gyratory device, a tool holder connected to said last named radially movable member, a worm rod journalled on said rotatable device and engaging the radially movable member thereon, a worm rod journalled on said gyratory device and engaging the radially movable member thereon, and driving connections 95 between said support and said rotatable device and said worm rod on said rotatable device for actuating said last named worm rod to move the radially movable member on said rotatable device to shift the axis of rotation of said gyratory device when said guiding means are revolved on their major axis.

38. In a machine of the character described, the combination of tool-guiding means comprising a rotatable device having a major axis of revolution, a support for said rotatable device, a member radially movable on said rotatable device, a gyratory device pivoted to said radially movable member, said radially movable member having a part constituting a separate axis of rotation for said gyratory device, a member radially movable on said gyratory device, a tool holder connected to said last named radially movable member, a worm rod journalled on said rotatable device and engaging the radially movable member thereon, a worm rod journalled on said gyratory device and engaging the radially movable member thereon, driving connections 115 between said support and said rotatable device and said worm rod on said rotatable device for actuating said last named worm rod to move the radially movable member on said rotatable device to shift the axis of rotation of said gyratory device when said guiding means are revolved on their major axis.

39. In a machine of the character described, the combination of tool-guiding means comprising a rotatable device having a major axis of revolution, a support for said rotatable device, a member radially movable on said rotatable device, a gyratory device pivoted to said radially movable member, said radially movable member having a part constituting a separate axis of rotation for said gyratory device, a member radially movable on said gyratory device, a tool holder connected to said last named radially movable member, a worm rod journalled on said rotatable device and engaging the radially movable member thereon, a worm rod journalled on said gyratory device and engaging the radially movable member thereon, driving connections 120 between said support and said rotatable device and said worm rod on said rotatable device for actuating said last named worm rod to move the radially movable member on said rotatable device to shift the axis of rotation of said gyratory device when said guiding means are revolved on their major axis.

40. In a machine of the character de-

vice for actuating said last named worm rod to move the radially movable member on said rotatable device to shift the axis of rotation of said gyratory device when said 5 guiding means are revolved on their major axis, and driving connections between said rotatable device and the worm rod on said gyratory device for actuating said last named worm rod to move the radially movable 10 member on said gyratory device to shift the axis of said tool holder when said guiding means are revolved.

39. In a machine of the character described, the combination of a rotatable device movable about a major vertical axis of revolution, a support for said rotatable device, a gear fixed to said support, an idler pinion mounted on said rotatable device and engaging said gear, a vertical shaft journaled in said rotatable device, a gear fixed to said shaft and in driving engagement with said idler pinion, a pinion fixed to said vertical shaft, a horizontal shaft journaled on said rotatable device, a driving 25 pinion for said horizontal shaft engaging said pinion on the vertical shaft, a block mounted for sliding movement on said rotatable device towards and from said axis of revolution, a stem depending from said block, a gyratory device pivoted on said stem, a pair of driving pinions for said gyratory device mounted on said horizontal shaft at opposite sides of said sliding block for selectively engaging the driving pinion 30 for said gyratory device, a worm rod journaled on said rotatable device, said sliding block being threaded to engage said rod, releasable driving connections between said horizontal shaft and said worm rod, where- 35 by said worm rod may be turned to shift said sliding block when said horizontal shaft is rotated.

40. In a machine of the character described, the combination with a member having a relatively fixed axis of revolution, a sliding block having a threaded opening and movable on said member, a second member pivoted to said sliding block to revolve with said first member and to rotate about the 45 vertical axis of said sliding block, a worm rod engaging the threaded opening in said block, means for actuating said worm rod and for rotating said second member, a worm wheel mounted on said first named 50 member and engaging said worm rod, and an indicating device connected to said worm wheel for indicating the extent of movement 55 of said sliding block on said worm rod.

41. In a machine of the character described, the combination of a work-supporting table, a standard associated with said table, a vertically movable spindle head mounted in said standard, a spindle sleeve 60 vertically movable in said spindle head, a spindle mounted to turn in said spindle 65

sleeve, tool-supporting and guiding means fixed to one end of said spindle, a lever pivoted to said standard, and interengaging parts on said lever and said spindle head whereby movement of said lever will raise 70 or lower said spindle head.

42. In a machine of the character described, the combination of a work-supporting table, a standard associated with said table, a spindle mounted in a part of said standard, tool-supporting and guiding means fixed to one end of said spindle, a shaft adjacent the other end of said spindle, driving connections between said shaft and the adjacent spindle end, a gear fixed to said shaft, a pinion-bearing arm releasably and adjustably secured to said standard, a pinion 75 removably journaled on said arm and in mesh with said gear, a countershaft adjacent said first named shaft and a driving 80 pinion on said countershaft meshing with the pinion on said arm, and driving connections between said countershaft and said table.

43. In a machine of the character described, the combination of a rotatable table and revolute members disposed in operative relation to said table, of a shaft and driving connections between said revolute members and said shaft, a gear for rotating 90 said table, a pinion fixed to said shaft, and a pair of intermeshing movably mounted pinions arranged so that one of the pinions may be engaged between said shaft pinion and said table gear or said pair of pinions 95 may be engaged in train between said shaft pinion and table gear, whereby said shaft and said table may be driven in the same direction or the drive may be reversed.

44. In a machine of the character described, the combination of a rotatable table and revolute members disposed in operative relation to said table, of a shaft and driving connections between said revolute members and said shaft, a gear for rotating said 105 table, a pinion fixed to said shaft, a plate mounted to swing about the axis of said shaft, and a pair of intermeshing pinions mounted on said plates, one of said pinions 110 engaging the pinion on said shaft and adapted when the plate is swung in one direction to establish a direct driving connection between said shaft and said table gear, the other of said pair of pinions being adapted to engage the table gear when the 115 plate is swung in another direction to reverse the drive between said shaft and table gear.

45. In a machine of the character described, the combination of a work-supporting table, a standard associated with said table, a spindle mounted in a part of said standard, tool-supporting and guiding means fixed to one end of said spindle, a shaft adjacent the other end of said spindle, 125

driving connections between said shaft and to said countershaft, a second countershaft, 10 the adjacent spindle end, a gear fixed to said a crank arm on said second countershaft of shaft, a pinion-bearing arm releasably and greater length than said first named crank adjustably secured to said standard, a pinion arm, a link connecting said crank arms, and 5 removably journaled on said arm and in driving connections between said second mesh with said gear, a countershaft adjacent countershaft and said table whereby rotation of said tool-supporting and guiding said first named shaft and a driving pinion on said countershaft meshing with means oscillates said table.

GEORGE L. KELLEY.
